UNITED STATES PATENT OFFICE.

HANCIL CORDREY, OF CHULA VISTA, CALIFORNIA.

COMBINATION OSTEOPATHIC AND CHIROPRACTIC TABLE.

Application filed April 5, 1922. Serial No. 549,866.

To all whom it may concern:

Be it known that HANCIL CORDREY, a citizen of the United States, residing at Chula Vista, in the county of San Diego and State of California, has invented a certain new and useful Combination Osteopathic and Chiropractic Table, of which the following is a specification.

My invention relates to a combination osteopathic and chiropractic table, particularly to a combination of separate tables of this class and the objects of my invention are: First, to provide an apparatus of this class in which one table is mounted above the other for economy of space and made collapsible with respect to the other; second, to provide an apparatus of this class in which the upper or osteopathic table is divided and in which the sections thereof are pivoted so that said table may be readily swung out of the way and thus permit accessibility to the table below; third, to provide an apparatus of this class in which the chiropractic table can be conveniently swung about its support to a nearly upright position so that the patient may conveniently mount the same while standing; fourth, to provide novel means in connection with said apparatus which will assist the chiropractor to readily handle the patient or lift the table upon which the patient is lying irrespective of the size or weight of said patient; fifth, to provide a multi-adjustable chiropractic table; sixth, to provide a novelly constructed combination of tables of this class and seventh, to provide an apparatus of this class which is very simple and economical of construction, durable, readily portable, easy to adjust and operate and which will not readily deteriorate or get out of order.

With these and other objects in view as will appear hereinafter my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a plan view of my combination osteopathic and chiropractic table; Fig. 2 is a side elevational view thereof; Fig. 3 is an elevational view taken from the foot end thereof; Fig. 4 is another elevational view taken from the other or head end thereof;

showing by dotted lines the upper or osteopathic table swung out of the way and resting on its edges at the base of the table; Fig. 5 is an enlarged fragmentary perspective view of one of the arms supporting the upper or osteopathic table; Fig. 6 is another side elevational view of my apparatus with the osteopathic table swung clear of the chiropractic table and resting on its edges at the side 2 of the chiropractic table, parts being broken away to facilitate the illustration and showing by dotted lines the nearly upright position of the latter table ready for a patient to mount the same, and Fig. 7 is a sectional view taken through 7-7 of Fig. 6.

Like characters of reference refer to similar parts and portions throughout the several views of the drawings.

The foot members 1, longitudinal base member 2, pedestal 3, support 4, beam 5, chiropractic table top sections 6, 7, and 8, osteopathic table top 9, supports 10, brackets 11 and 12, links 13, footrest 14, slide blocks 15 and 16, retaining pins 17, hinge 18, brackets 19, upper hinge members 20, adjusting members 21, springs 22, pivot shaft 23, journals 24, tension member 25, roller 26, tension spring 27, eye bolt 28, supports 29, hinge members 30, catch member 31 and the spring 32 constitute the principal parts and portions of my apparatus.

The longitudinal base member 2 is provided at its ends with transverse foot members 1 secured thereto. Said base member is further provided near one end thereof with a pedestal 3, open at the rear side thereof, extending upwardly from said base member and secured thereto. Mounted on the upper face of said pedestal and on either side of the open portion therein are the journals 23. A beam 5, provided near one end with a pivot shaft 22 extending transversely therethrough, is pivotally mounted on said shaft in and between said journals 23. A support 4 is provided at the other end of said base member 2 adapted to support the extended free end of the beam 5.

The pedestal 3 and support 4 are provided near their upper ends and on one side thereof with substantially U-shaped osteopathic table supports 10 secured thereto. Said table supports are provided at their upper free ends with hook portions 10^a extending inwardly therefrom as shown best in Fig. 5 of the drawings. The osteopathic table top is divided into two sections 9^a and

9^b which are provided on the under sides thereof with downwardly and outwardly extending brackets 11 and 12 respectively. The normally upper portion of said brackets 5 extend inwardly a short distance beyond the inner edges of said osteopathic table sections, thus providing a support for each other. The brackets 11 and 12 are pivotally secured at their lower free ends to the free 10 ends of the links 13, the other ends of the latter being pivotally mounted near the lower portion of the support 10. It will be here noted that the hook portion 10^a of the U-shaped supports 10, as previously described, are provided to support the upper or free ends of the links 13, thus supporting and securely positioning the sections 9^a and 9^b of the osteopathic table top 9 against each other. The footrest 14 extends upwardly and at an angle from and is secured to the short end of the beam 5 and is adapted to also serve as an auxiliary support for the osteopathic table sections.

The beam 5 is provided with longitudinal 25 grooves 5^a on either side thereof extending from the free end of the same backwardly towards its pivot. Shiftably mounted on said beam are the slide blocks 15 and 16 guided and retained by the grooves 5^a there- 30 in. Said beam is further provided with a plurality of spaced holes 5^b extending transversely therethrough adapted to receive the retaining pins 17. The slide blocks 15 and 16 are provided with similar oppositely 35 disposed holes 15^a and 16^a coinciding with the holes 5^b of the beam 5, thus providing means for securing said slide blocks in various positions on said beam. The slide blocks 15 are provided with hinge brackets 40 18 secured to the upper faces thereof. Pivotally mounted at the upper portion of the hinge bracket 18, secured to the slide block 15 mounted near the free end of the beam 5, is the upper hinge member 19 secured to the under side of the head section 45 6 of the chiropractic table top which is adapted to support the upper portion of the patient's body. The foot section 8 of the chiropractic table top, adapted to support 50 the lower portion of the patient's body, is similarly provided at the under side thereof with a hinge member 19 which is similarly mounted on the slide block 15 near the other end of said beam 5. The chiropractic table top sections 6 and 8 are further provided 55 at the under side and near the free ends thereof with other hinge members 30 which are pivotally secured in the upper ends of the adjusting members 20. Said adjusting 60 members are provided with a plurality of spaced, oppositely disposed holes 20^a adapted to receive the pin 17 therethrough positioning and securing said adjusting members on the beam 5 at the holes 5^c also 65 extending transversely therethrough. The

slide blocks 16 positioned on the beam 5 intermediate said slide blocks 15 is provided with outwardly extending bracket portions 16^b. Mounted on said bracket portions and extending upwardly therefrom are the 70 springs 21. The table section 7 of the chiropractic table top is secured to the upper free end of said springs, thus providing a resilient abdominal support section in said chiropractic table. The foot rest 14 is provided near the short end of said pivoted beam 5, as described above, to provide a rest or brace for the patient on the chiropractic table and for the purpose of assisting him to mount or dismount the same. A flexible 75 tension member 24 is secured to the short end of said beam and extends downwardly around the roller 25 revolvably mounted on the roller axle 26 which is secured in the side portions 2^a and 2^b of the hollow base member 2, the free end of said tension member is secured to the tension spring 27 concealed in the hollow portion of said base member. An eye bolt 28 is provided in the head end of the base member 2 to secure the other end of said spring. A catch member 31 is pivotally mounted on the under side of the beam 5 near the free end thereof adapted to engage the projection 10^b on the support 10 secured to the upper portion of the support 4. A compression spring 32 is interposed between the under side of said beam and the extended portion of the catch member 31, thus providing a convenient and positive means for securing said beam 100 against the support 4. The supports 29 secured to the foot members and the longitudinal base member are provided to support the osteopathic table section when not in use and folded downwardly.

It is obvious that by raising the inner portion of the osteopathic table top sections and forcing the brackets 11 and 12 secured thereto towards each other, the links 13 mounted on the other ends thereof 110 are disengaged from the hook portion 10^a of the U-shaped support 10. It will also be noted that by exerting a slight force on said osteopathic table sections 9 in the direction of the head end thereof when the same 115 is raised as described above, the links 13 will be shifted out of line with the hook portion of the support 10, thus permitting the same to be pulled past said hook portion and also permitting the said table sections to be swung outwardly into the position shown by dotted lines in Fig. 4 of the drawings, resting on the brackets 29.

It is further obvious that when the osteopathic table top sections are swung free of the chiropractic table member sections as described above and when the catch member 31 is disengaged from the projected portion of the support 10, the beam 5 supporting the various chiropractic table member 120

sections is permitted to swing about in the journal 23 assisted in its rotation or upward movement by the tension spring 27 concealed in the base member 2 acting directly on the tension member 24 secured to the short end of the beam 5. The chiropractic table members shown by dotted lines in a nearly upright position in Fig. 6 of the drawings is in a position for the patient to mount prior to taking treatments.

Though I have shown and described a particular construction, combination and arrangement of parts and portions I do not wish to be limited to this particular construction, combination and arrangement but desire to include in the scope of my invention the construction, combination and arrangement substantially as set forth in the appended claims.

Having thus described my invention what I claim as new and desire to secure by Letters Patent is:

1. In an apparatus of the class described, a pedestal, a beam pivotally mounted near one end thereof on said pedestal, a tension means secured to the short end of said beam and to said pedestal adapted to move said beam to a substantially upright position, means adapted to secure said beam in a substantially horizontal position, multi-adjustable table sections shiftably mounted on said beam, osteopathic table sections pivotally mounted over said chiropractic table adapted to be swung clear of, to the side of and below said chiropractic table sections and supports adapted to secure said osteopathic table sections in position over said chiropractic table.
  2. In an apparatus of the class described, a pedestal, a beam pivotally mounted on said pedestal, means adapted to secure said beam in a substantially horizontal position, multi-adjustable table sections shiftably mounted on said beam, osteopathic table sections pivotally mounted over said chiropractic table adapted to be swung clear of, to the side of and below said chiropractic table and supports adapted to secure said
- osteopathic table sections in position over said chiropractic table.
3. In an apparatus of the class described, the combination of a multi-adjustable chiropractic table and a collapsible osteopathic table operatively connected therewith and movable around to the sides and above said chiropractic table.
  4. In an apparatus of the class described, a longitudinal base member, a pedestal mounted near one end of said base member, a beam pivotally mounted near one end at the upper face of said pedestal, a support secured to the other end of said base member adapted to support the free end of said beam in a substantially horizontal position, tension means secured to the short end of said beam and in the hollow portion of said longitudinal base member adapted to move said beam to a substantially upright position, means secured to the free end of said beam and the upper portion of said support adapted to secure said beam in a substantially horizontal position, multi-adjustable chiropractic table sections shiftably mounted longitudinally on said beam, substantially U-shaped supports, mounted on the upper portions and on one side of said pedestal and said support extending upwardly and to either side therefrom provided with hook portions on said extended ends, links pivotally mounted at the lower portion of said U-shaped supports, and osteopathic table sections provided with brackets on the under side thereof pivotally mounted in and to the free ends of said links.
  5. In an apparatus of the class described, the combination of base members, a multi-adjustable full length chiropractic table pivotally mounted near one end on one of said base members and an osteopathic table extending the full length of said chiropractic table secured to said base members.

In testimony whereof, I have hereunto set my hand at San Diego, California, this 29th day of March, 1922.

HANCIL CORDREY.
